FRACTURE APPLIANCE

Benjamin F. Tofflemire, Bremerton, Wash.

Application July 26, 1943, Serial No. 496,241

4 Claims. (Cl. 128—76)

My invention relates to improvements in fracture appliances especially designed for the reduction and fixation of mandibular fractures and it consists of the combinations, constructions and arrangements hereinafter described and claimed.

An object of my invention is to provide a compact, all-metal, boilable and universally adaptable mandibular fracture appliance. The device has an infinite number of adjustments to adapt it to any particular fracture and the positive fixation of all moving parts are controlled with a single wrench. The adjusting nuts holding the movable parts together face outward where they are readily accessible without having to move the patient.

The appliance may be assembled as a unit and then folded into a minimum of space for storage or transportation. The device may be opened up like a book and a preliminary fitting made without the bone screws being in place and before the patient is taken into surgery. The entire unit may then be placed in a sterilizer along with the bone screws and the instruments used in the operation and rendered sterile before or during the induction of anesthesia. Since the entire unit is adjusted to the approximate size and conformation necessary in advance, it is merely necessary to place the bone pins in the previously determined and marked positions, reduce the fracture and securely fasten the parts together by tightening the bolts with the wrench. This eliminates much of the delay, effort and annoyance incident to the assembling of a device using scattered parts.

A further object of my invention is to provide an appliance having a minimum number of horizontally placed rods and fixation equipment. By reducing this lateral bulk, the patient can turn his head from side to side without danger of bumping into anything lying near his face. The patient may lie on either side of his face on a pillow which is impossible with all other extra-oral skeletal fixation devices having their connecting rods and clamps placed on a "horizontal-bank" principle resulting in the patient having a cumbersome aggregation of rods, clamps, bolts and nuts extending outward on either side and forward of the face. The consequent inability to lie in any other position than flat on the back, together with the constant apprehension of bumping into anything that might come near the shoulder or face, creates an undesirable psychological reaction in the patient. My device overcomes these disadvantages.

A further object of my invention is to provide

a device that utilizes the anatomical configuration of the human chin in such a manner that the patient has complete vertical freedom of the head in a forward nodding position and also a horizontal rotation-freedom of the head. The structure of the device permits unlimited adjustment in both a horizontal and vertical plane. The device will fit varying sizes and shapes of human jaws and permit freedom of the chin in chewing. It is possible to insert the bone-pins at a higher level than is possible with other devices without danger of violating the structures within the mandibular canal. The bone-pins can therefore be directed downward and inward through the body of the mandible; anteriorly, downward and backward, utilizing the additional strength of bone at the mental protuberance, profit by the natural anatomical "shelf" of bone in this area, and avoid the apices of the anterior teeth.

10 The device is compact, flexible and adaptable for all types of jaws and permits freedom of jaw movement and greater comfort to the patient. When the device is tightened in place, it will give positive fixation and immobilization of parts.

15 Other objects and advantages will appear in the following specification, and the novel features of the device will be particularly pointed out in the appended claims.

20 My invention is illustrated in the accompanying drawing forming a part of this application, in which:

Figure 1 is a plan view of the device shown applied to a jaw;

25 Figure 2 is a front elevation of the central part of Figure 1, and illustrates the use of a curved chin-bow;

30 Figure 3 is a side elevation of the fracture appliance, looking in the direction of the arrow 3 in Figure 1;

35 Figure 4 is an enlarged vertical section through one of the clamps used in the device;

40 Figure 5 is an enlarged vertical section through a bone-pin retainer; and

45 Figure 6 is a plan view of a simplified appliance for unilateral fracture.

While I have shown the preferred forms of my invention, it should be understood that various changes or modifications may be made within the scope of the appended claims without departing 50 from the spirit and scope of the invention.

In carrying out my invention, I provide a multiple mandible unit shown in Figures 1, 2 and 3 for bilateral, comminuted fractures involving more or less extensive displacement, distortion and deformation of the bone fragments. In Figure 6, I

illustrate a simplified unit for unilateral fractures of the mandible. I will first describe the multi-mandibular unit and then the simplified unit.

The multiple-mandible unit comprises a face bow A consisting of two L-shaped parts 1 and 2 hinged together at 3 and having downwardly extending posts 4 and 5. Infra-mandibular suspension rods B and C have vice-grip clamps 6 and 7 disposed at one end that grip the posts 4 and 5 and permit the rods B and C to be rotated on the posts and adjusted longitudinally therealong into the desired position before the nuts 8 and 9 are tightened to secure the rods rigidly to the posts. Figure 2 shows the rods B and C without the T-bar pin retaining unit for purpose of clarity.

Figures 1 and 3 illustrate the T-bar pin retaining units indicated generally at D and E. Each unit is identical so a description of the unit E will suffice for both and corresponding parts will be given like reference numerals. A vertical rod 10 is adjustably secured to the rod C by a clamp F. This clamp is shown in detail in Figure 4 and permits the T-bar to be adjusted longitudinally along the rod C and the vertical rod 10 to be adjusted vertically in the clamp. A single nut 11 may be tightened and will cause the clamp F to grip both rods C and 10.

The clamp F comprises a bolt 12 with a head 13 that has a reduced cylindrical portion 14 for receiving a sleeve 15. The head 13 has a transverse bore 16 therein for receiving the rod C. The sleeve 15 is slightly longer than the length of the reduced portion 14. A bifurcated member 17 has aligned openings 18 for receiving the bolt 12 and has a bore 19 extending at right angles to the axis of the openings 18 and designed to receive the vertical rod 10. The slot 20 forming the bifurcation communicates with the bore 19. A tightening of the nut 11 will clamp the rod 10 and force the sleeve 15 to clamp the rod C, thus locking the parts together. The rod 10 may be rotated in the bore 17 and adjusted longitudinally into the desired position.

The T-bar E has a top bar 21 carried by a depending member 22 which in turn is pivotally connected to the top of the rod 10 by a bolt and nut 23. The bar 21 may be swung into angular positions with respect to the bar 10 and locked in adjusted position by the nut 23. Bone-pin retainers G are adjustable along the bar 21 and may be clamped in the desired angular position. An enlarged detail section of the retainers G is shown in Figure 5.

The bone-pin retainer G comprises a bolt 24 with a head 25 and the bolt has a transverse bore 26 extending therethrough with a part of the bore extending into the underside of the head. The bore 26 removably receives a bone-pin H and a plate 27 bears against the pin. The plate 27 has a groove 28 for receiving the bar 21. A second or lower plate 29 has a groove 30 in its upper surface for receiving the bar 21. The plates 27 and 29 have aligned openings 31 and 32 therein for receiving the bolt 24 and a nut 33 tightened on the bolt 24 locks the retainer G on the bar and locks the bone-pin H in the desired angular position.

The T-bar, pin-retaining units D and E are placed in the region of the angle of the jaw on either side and the bone-pins H are inserted at the desired angle so that they will converge inward, see Figures 1 and 3. The vertical rods 10 should clear the cheeks and jaw and these rods are secured to the infra-mandibular suspension

rods B and C by the clamps F. The clamps F permit unlimited movement in any desired direction and under the control of a single retaining bolt which instantly immobilizes all moving parts when the one fixation bolt 12 is secured by the nut 11.

The infra-mandibular connecting rods B and C extend forward toward the chin, on either side, see Figure 1, to a point opposite the mental foramen, where the rods connect to the chin posts 4 and 5 of the face bow A. The clamps 6 and 7 secure the rods to the posts with a vice-grip while permitting adjustment or a rotating expansion or contraction to accommodate the differences found in individual faces and different types of injuries. The face bow A has an additional adjustment by means of the centrally placed hinge-joint 3 at the mandibular symphysis.

Upon the horizontal portion of the face bow may be fitted as many pin retaining units J as are needed to take care of the comminuted segments of bone. Frequently a single bone pin H on either side of the symphysis will take care of the anterior support where no comminuted segments are to be transfixed. This does away with the bilateral pairs of twin-pin attachments used in the mental foramen region by other contemporary fracture appliances. While very little disfigurement if any, is caused by the bone-pins, the saving of additional trauma is a distinct advantage in multiple-mandible cases.

The pin retaining unit J is illustrated in Figures 1 and 2 and comprises U-shaped members 34 adapted to straddle the face bow and having slots 35 for receiving the bone-pins. A set screw 36 is carried by the member 34 and bears against the face bow to clamp the bone-pin H thereagainst. The retainer J may be detached from the pin and face bow without disturbing any other part of the assembly.

In those cases where long posterior segments of edentulous jaws are adversely affected by strong muscular pull with resulting displacement, a chin bow K is used, see Figure 2. The chin bow has short rods 37 and 38 pivoted at its ends as at 39 and 40 respectively and so designed that the hinged rods maintain a parallel relationship with the infra-mandibular rods B and C. Rod clamps L secure the hinged short rods to the rods B and C. The rod clamps L are shown in Figure 1, although where the chin bow is not used, the rod clamps are also not used.

In use, the chin bow K is attached to the connecting rods B and C by the rod clamps L in approximately the position the chin bow is to occupy. One side, for example the side with the rods 38 and C, is securely fastened by tightening the hexagon nut 41 on the clamp L engaging with these rods. The infra-mandibular rods on the appliance are then either rotated outward or inward as the fragments may require, and the other parallel rod clamp J is then tightened by the nut 41 as well as the vice grip clamps 6 and 7 are tightened.

The face bow fits into the horizontal depression normally existing in the area between the lower lip and chin. Utilizing this incisive fossa permits the patient to have complete vertical freedom of the head. The vertical posts 4 and 5 provides a common rotation center for each rod B and C at the position of the mental foramen. Freedom to the chin for chewing is provided and this would not be possible if the infra-mandibular suspension principle were continued anterior to

the area of the mental foramen, instead of being diverted vertically at this point to become a part of the horizontal face bow extending across the incisive fossa.

The mandibular canal contains the inferior alveolar vessels and nerves and these structures emerge from the mandibular canal by means of the mental foramen on either side of the jaw approximately below the lower first bicuspid tooth for anterior distribution and the mandibular canal ceases to exist as such in the anterior portion of the mandible, between the right and left mental foramen. This permits the use of the incisive fossa at the point of the chin for the horizontal portion of the face bow. This permits a form-fitting appliance to be used and reduces the external bulk of the device. The bow-pins may be inserted at a higher level without danger of violating the structures within the mandibular canal since this is non-existent anterior to the posts 4 and 5. The bone pins converge toward the tips and are directed away from the membranes on the floor of the mouth thereby avoiding the possibility of contamination of a surgically clean field of operation with saliva and blood from the mouth, an area that is impossible to maintain in an aseptic condition. The pins can extend at any desired angle and will be clamped in place.

In Figure 6, I show the simplified unit, and it comprises a hinged connecting rod M upon which the pin retaining units G are placed in such a manner that two pins H are inserted in the bone on either side of the fracture. The pin retaining units on one side of the hinge M' are made secure to the pins and the rod by merely tightening the hexagon nuts 33 (not shown in Figure 6, but shown in Figure 5) after the pins have been screwed into the jaw. The two pins inserted in the jaw on the other side of the fracture are secured to the rod M on the other side of the hinge by pin retaining units after the fracture is reduced. By using a hinged rod M it is possible to line up the two pins on one side of the hinge and the two pins on the other side with the two arms of the rod and then tighten the nut for locking the hinge M' from movement.

Normal apposition of the bone ends may be readily checked by the occlusal relationship of the teeth in centric occlusion. The excess ends of the bone pins should be cut off. The connecting rod M will maintain vertical as well as horizontal alignment for the fracture with a minimum equipment and bulk. The patient may use his jaws with a reasonable degree of freedom. There is no contamination with the flora of the mouth. The patient will have no aggregation of arches, wires and elastics within the mouth to gather food debris and interfere with normal oral hygiene. The patient will not have to subsist on a liquid diet and he will not have loose teeth, spongy gums and the unsanitary disuse atrophy changes so often found in cases of intermaxillary fixation. All of the parts are fastened together by hexagonal nuts permitting a single wrench to tighten all of the parts or loosen them.

The device shown in Figure 6 with the hinged rod M may be used on anterior mandibular fractures instead of the more complicated face-bow attachment wherever there are not additional unilateral or bilateral involvements in the body of the mandible.

I claim:

1. A fracture appliance comprising a face bow with parallel and downwardly extending posts, infra-mandibular rods, means for swingably and adjustably supporting the rods on the posts and adapted to be tightened in position so as to underlie the cheeks of the wearer, T-bars, means for slidably supporting the T-bars on the rods and securing them thereto, bone-pins, means for securing certain of the pins on the face bow, and means for securing the other pins to the T-bars with freedom of angular and longitudinal adjustment.
2. A fracture appliance comprising a hinged face bow with parallel and downwardly extending posts, infra-mandibular rods having clamps slideable along the posts for securing them in the desired angular positions on the posts so that the rods underlie the cheeks of the wearer, T-bars, clamps securing the T-bars to the rods so that the T-bars extend above the rods, said T-bars having short rods, means pivoting the short rods to the T-bars and adapted to secure them in adjusted position, bone-pins, means for securing certain of the pins on the face bow on either side of the hinge, and bone-pin retaining units adjustable along the short rods and permitting the other pins carried thereby to be inclined at the desired angles, said retaining units locking the pins in place.
3. A fracture appliance comprising a hinged face bow with parallel and downwardly extending posts, infra-mandibular rods having clamps slideable along the posts for securing them in the desired angular positions on the posts so that the rods underlie the cheeks of the wearer, T-bars, clamps securing the T-bars to the rods so that the T-bars extend above the rods, said T-bars having short rods, means pivoting the short rods to the T-bars and adapted to secure them in adjusted position, bone pins, means for securing certain of the pins on the face bow on either side of the hinge, bone-pin retaining units adjustable along the short rods and permitting the other pins carried thereby to be inclined at the desired angles, said retaining units locking the pins in place.
4. A fracture appliance comprising a face bow with parallel and downwardly extending posts, infra-mandibular rods, means for swingably and adjustably supporting the rods on the posts so that the rods will extend along the under sides of the jaw and cheeks, said means tightening the rods in position, T-bars having vertically extending members with members normally extending at right angles thereto but which may be swung into angular positions with respect to the vertical members, means for slidably supporting the vertical members on the rods so that the other members will be spaced the desired distance above the rods and permit the rods to underlie the cheeks, said last-named means permitting the vertical members to be rotated into the desired angular positions before tightening them in place, means for securing said other members to the vertical members at the desired angular positions for causing both members to lie close to the face, bone pins, and means for securing certain of the bone pins to the face bow and others to the said other members on the T-bars at the desired angles.
